Patented Aug. 3, 1920.

UNITED STATES PATENT OFFICE.

JOHN W. COAST, JR., OF TULSA, OKLAHOMA, ASSIGNOR TO THE PROCESS COMPANY, A CORPORATION OF MARYLAND.

ART OF CRACKING HYDROCARBONS.

1,348,266.

Specification of Letters Patent. Patented Aug. 3, 1920.

Application filed March 27, 1917, Serial No. 157,629. Renewed June 14, 1920. Serial No. 389,008.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Cracking Hydrocarbons, of which the following is a full, clear, and exact description, reference being had to the accompanying 10 drawings, forming a part of this specification.

My invention relates to improvements in the art of cracking petroleum hydrocarbons, one of the objects being to protect cracking 15 stills from the injurious effects of coke-forming substances which tend to accumulate on the hottest parts of the stills. This feature of the invention increases the efficiency of a cracking apparatus by circulating the coke, or carbon, away from the point at which heat is transmitted to the still, thus permitting the heat to be transmitted freely from the still to the oil, at the same time avoiding the danger of overheating 20 the metal of the still, and allowing the apparatus to remain in service for a considerable period of time. I attain this object by permitting the liquid to overflow from one cracking still to another and removing 25 the coke-forming substance from the overflowing liquid. This coke-forming substance consists of heavy fractions which drop by gravity to the lower portion of the liquid in the still, and the overflowing liquid is therefore 30 preferably conducted from the lower portion of one still, through a coke-trap, and then into another still. 35

Figure I is a diagrammatical view, partly in section, of a cracking apparatus adapted 40 for use in carrying out my method.

Fig. II is a diagrammatical perspective view, showing a battery of cracking stills connected by overflow conductors.

Fig. III is an enlarged vertical section 45 illustrating one of the coke-traps.

To illustrate the invention, I have shown a battery of cracking stills designated 1, 2, 3 and 4, respectively. Each cracking still is arranged above a heating chamber 5 and 50 connected by means of an air cooled vapor pipe 6 to a reflux condenser 7, said condenser 7 being connected by means of a vapor pipe 8 to a water cooled condensing coil 9, from which the low boiling point product is recovered. Each vapor pipe 8 is preferably

provided with a valve 10 for regulating the pressure.

The apparatus I have shown is particularly adapted for use in cracking high boiling point products of distillation, such, for example, as the distillates or residues resulting from the distillation of petroleum. The pressure in the battery of stills is preferably greater than 50 pounds per square inch, and the temperature of the contents of the stills preferably ranges from about 600° F. to 800° F. Heat is transmitted directly through the bottoms of the stills so as to vaporize and crack the oil contained therein. The heavy coke-forming fractions drop by 70 gravity in the liquid and tend to accumulate on the hot still bottoms.

The object of this invention is to remove the coke-forming fractions by causing the liquid to overflow from the bottom of one 75 still, through a coke-trap and then into another still, the coke-forming substance being thus circulated from the lower portion of the first mentioned still and deposited in the coke-trap. The oil to be cracked is 80 forced through a pipe 11 and into the still 1, from which it overflows and circulates into the other stills. The different stills are connected together in series, as shown in Fig. II. An overflow conductor 12 leads 85 from the lower portion of the still 1 to the lower portion of a coke-trap 13, and the upper portion of the coke-trap is connected to the still 2 by means of a pipe 14. The liquid overflowing from the still 1, passes 90 out through the pipe 12, and is discharged into the lower portion of the coke-trap 13. The heavy coke-forming fractions are permitted to accumulate at the bottom of the coke-trap, and the lighter liquid overflows 95 from the upper portion of the coke-trap and circulates into the still 2. A large percentage of the heavy, coke-forming substance is thus conducted to the coke-trap 13, where it will not in any way injure or affect the 100 cracking apparatus. The coke, or tarry, coke-forming substance, may be removed from the trap 13 by opening a valve 15 in the discharge pipe 16.

The liquid overflowing from the lower 105 portion of the still 2, passes through a pipe 12' and into a coke-trap 13', the relatively light liquid being permitted to overflow from said coke-trap 13' through a pipe 14' and into the still 3. The stills 3 and 4 are 110

connected by means of an overflow pipe 12', a coke-trap 13' and an overflow pipe 14'. The overflow conductors place the different stills in free communication with each other, 5 and a uniform pressure is therefore maintained in all of the stills. This pressure is also maintained in the coke-traps and overflow pipes. All of the overflowing liquid must circulate through a coke-trap, wherein 10 the heavy coke-forming substance will drop by gravity instead of passing from one still to another.

I claim:

In the art of cracking hydrocarbons, the 15 method which comprises maintaining the contents of a battery of horizontal cylindrical cracking stills under pressure, and in free

communication with each other so as to equalize the pressure in the several stills, introducing the oil to be cracked into the battery of stills by conducting the oil into one of the stills and permitting it to overflow in a liquid state into the other stills, the overflowing oil being conducted from the lower portion of one still through a coke-trap and into another still so as to carry coke-forming fractions from the bottom of the overflowing still to the coke trap, and heating the bottoms of the stills to maintain the oil at a cracking temperature. 20 25 30

In testimony that I claim the foregoing I hereunto affix my signature.

JOHN W. COAST, JR.
